UNITED STATES PATENT OFFICE

101,093

DESIGN FOR RECEPTACLE FOR MANICURE IMPLEMENTS OR SIMILAR ARTICLE

Lewis Douglas Young, Providence, R. I., assignor to Douglas Young, Inc., a corporation of Rhode Island

Application March 14, 1936, Serial No. 61,632

Term of patent 7 years

To all whom it may concern:

Be it known that I, Lewis Douglas Young, a citizen of the United States of America, residing in Providence, county of Providence, State of Rhode Island, have invented a new, original, and ornamental Design for a Receptacle for Manicure Implements, or Similar Article, of which the following is a specification, reference being had to the accompanying drawing, forming a part thereof.

Fig. 1 is a perspective view of a receptacle for manicure implements, or similar article, showing my new design; and Fig. 2 is a similar view with the cover opened, of the same.

The rear face of the receptacle for manicure implements, or similar article embodying my novel design has the same appearance as the front face thereof when the latter is closed except that there is no latch or tab extending from the rear face.

I claim:

The ornamental design for a receptacle for manicure implements, or similar article, substantially as shown and described.

LEWIS DOUGLAS YOUNG.
